US0D1008951S

(12) **United States Design Patent** (10) Patent No.: **US D1,008,951 S**
(45) Date of Patent: ** Dec. 26, 2023

(54) **RECHARGING HOLDER FOR ELECTRIC
TOOTHBRUSH**

(71) Applicant: **Braun GmbH**, Kronberg (DE)

(72) Inventors: **Devran Albay**, Frankfurt (DE); **Moritz
Carlo Honisch**, Frankfurt (DE);
Dominik Langhammer, Frankfurt
(DE); **Rüdiger Boss**, Frankfurt (DE);
Fritz Schubert, Bad Camberg (DE)

(73) Assignee: **Braun GmbH**, Kronberg (DE)

(**) Term: **15 Years**

(21) Appl. No.: **29/774,467**

(22) Filed: **Mar. 17, 2021**

(57) **CLAIM**

The ornamental design for a recharging holder for electric toothbrush, as shown and described.

DESCRIPTION

FIG. 1 is a perspective view of a recharging holder for electric toothbrush;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

1 Claim, 2 Drawing Sheets
